UNITED STATES PATENT OFFICE

JAMES J. R. McLOUGHLIN, OF POLAND, NEW YORK

DESIGN FOR A CASING FOR A MOTOR OIL DISPENSER

Application filed May 4, 1932. Serial No. 43,710. Term of patent 3½ years.

To all whom it may concern:

Be it known that I, JAMES J. R. McLOUGHLIN, a citizen of the United States, residing at the village of Poland, county of Herkimer, State of New York, have invented a new, original, and ornamental Design for a Casing for a Motor Oil Dispenser, of which the following is a specification reference being had to the accompanying drawing, forming part thereof.

The figure is a perspective view of the casing for a motor oil dispenser, showing my new design. The feature of surface ornamentation is not duplicated upon the opposite side of the dispenser but on the other hand, the opposite side is plain without any ornamentation.

I claim:

The ornamental design for a casing for a motor oil dispenser, as shown and described.

JAMES J. R. McLOUGHLIN.
